UNITED STATES PATENT OFFICE.

RUDOLPH ORTHWINE, OF NEW YORK, N. Y.

DISPLAY CABINET.

Application filed March 3, 1927. Serial No. 172,270.

My invention relates to display cabinets particularly adapted for holding stocks of various small articles and suitable for convenient dispensing and sale thereof, for the 5 ready maintenance and display of the stock in orderly condition and attractive appearance and for protection against dust and tampering.

Modern merchandising methods require 10 the rapid dispensing of large quantities of many small items, such as candies, toilet articles, small hardware items, and such like material, with a minimum expenditure of time and labor on the part of the salesman. 15 It is required in order to promote the rapid efficient sale of them, that the articles sold be kept in good order, with the bins nearly full, and that protection be provided against dust and injury to the articles, and also 20 against any other injury such as tampering and loss. These requirements necessitate a compact, inexpensive cabinet, with provision for the convenient subdivision into a plurality of adjustable bins, and with provision 25 for the use of subpositioned filler members to take the place of removed stock, in order that the cabinet may not show nearly empty bins as the stock is sold out. It is further required that some means be provided for 30 the protection of the stock against dust, tampering and pilfering.

My invention provides a simple, inexpensive, dispensing cabinet as disclosed in my copending application Serial No. 172,269 35 filed March 3, 1927, in combination with a simple, convenient, and easily removable, covering means comprising a cooperating frame readily attachable to the structure previously disclosed, and providing a pair of guideways and a pair of sliding glass panes positioned therein, adapted to cover and protect the dispensable stock. By my invention I am enabled to provide a simple, convenient, inexpensive, durable cabinet, 40 with sliding glass panes for protection of the stock, in combination with means whereby the bins are readily adjustable in dimensions to the size of the articles stored therein, and whereby the top surface of the 45 stock of goods is maintained near the top of the bin and near the under surface of the glass, for convenient inspection by a prospective purchaser without the necessity for uncovering the stock until the sale is made.

50 Other objects and structural details of my invention will be apparent from the follow-

ing description when read in connection with the accompanying drawings, wherein:

Fig. 1 is a perspective view of an embodiment of a preferred form of the device of 60 my invention;

Fig. 2 is a vertical transverse section of the same embodiment;

Fig. 3 is a vertical lengthwise section of the cover portion of the same embodiment; 65

Fig. 4 is a vertical section of a portion of the edge of the stand, cover frame, and glass, and

Figs. 5 and 6 show details of the corner construction of the cover frame. 70

The preferred embodiment of my invention, shown in the drawings, which may be designated generally as a hollow frame, comprises sheet metal side members 1 and 2, a front member 3, a back member 4 and bottom member 5, partition members 6, and partial level top wall, forming a table 19. The partition members 6 are provided with grooves 7, as indicated, and bottom members 8 are attached to and positioned between the partition members 6 for the formation of compartments. Movable partition members 9 are provided having lug members 10 with projections thereon cooperating with the grooves 7 to hold the movable partition members accurately in a vertical position. The cabinet is thus divided into compartments of adjustable size. The partition members 6 may be provided with card racks 11 for the support of price cards, descriptive matter, or advertisements, etc. Filler members 12 are also provided and adapted to be removably positioned within the bins, to raise the level of the bottom thereof, and thereby to reduce the capacity 85 of the bin in accordance with a reduction in contained stock, so that in spite of the diminishing of the stock through sales, the upper surface is kept approximately at the top of the bin. 95

My invention further provides a frame member 14 adapted to fit inside of the cabinet portion as previously described, by a simple, snug friction fit. The upper edge 100 of the frame member 14 is bent to form channels 15 and 16 as shown, forming sets, within which are positioned the panes of glass 17 and 18. The panes are superposed one above the other in the grooves and are, in length, little over half of the length of the cabinet, that is, they are in extent only 105 a fraction longitudinally of the top opening. 110

They are accordingly adapted to slide from side to side of the cabinet in their superposed position. The glass panes are desirably provided with appropriate finger grips, which may be openings made into the glass at suitable points, or may be metal handles bolted in place through holes in the glass. By the preferred embodiment, the glass panes are mounted directly within the 10 grooves in the frame and may, if desired, be provided with a felt padding to facilitate the moving therein. Alternatively, where it is found necessary to provide further protection to the glass, the panes may 15 be mounted in metal subframes which in turn are adapted to slide within the grooves in the main frame. In this embodiment suitable handles may be provided in connection with the metal frame.

20 The cover frame 14 is desirably made in two parts, one part comprising three sides thereof, and another part comprising the fourth side. This is convenient for the ready removal and insertion of the glass 25 panes, both at the time of assembly and in the event that the glass is broken and needs replacement, as may happen in the course of usage. The fourth side is desirably held in place by a screw at each end cooperating 30 with corner block members having threaded openings therein, as shown in detail in Figs. 5 and 6.

The first partition 6 to the left of rear wall 4, as shown in Fig. 2, descends vertically from the front edge of the partial top 35 19, so that no goods are under the top or table and so perhaps in darkness or difficult to reach, so that by such construction, although the useful table top is provided it 40 does not act to hide the goods. By this construction all goods in the case are equally well exposed but nevertheless a table is provided upon which the various operations usually connected with the sale of goods may 45 be performed.

By my construction, I thus provide a dispensing cabinet, having a glass cover, with means whereby the stock of dispensable goods is readily maintained at all times adjacent the under surface of the glass, thereby 50 facilitating inspection by a purchaser without the necessity of uncovering the stock. I thus provide a highly convenient dispensing cabinet with means for protection of the stock against dirt and pilfering, in combination with means for the most advantageous possible display thereof to purchasers.

While I have shown but a single embodiment of the device of my invention in the accompanying description, it is capable of 60 various modifications therefrom without departing from the spirit thereof, and it is desired, therefore, that only such limitations shall be imposed thereon as are required by the prior art or indicated by the appended 65 claim.

I claim as my invention:

In a display cabinet, in combination: a hollow frame formed by side walls, a front wall and a rear wall, a bottom wall, and a 70 partial level top wall forming a table, said front wall being lower in height than said rear wall and said side walls being formed on the upper edge to slope from the top of the front wall to a point slightly below the 75 top wall vertically below the front edge of the top wall; a longitudinal partition extending down into the space of the frame depending from the front edge of the partial top wall; a frame member having depending 80 flanges and formed with sets of slide channels resting upon the side walls and front wall and abutting the said vertical partition and glass panes, one fitting in each of the sets of channels, each pane being in extent only a fraction longitudinally of the top opening of the frame.

In witness whereof, I hereunto subscribe my signature.

RUDOLPH ORTHWINE
